UNITED STATES PATENT OFFICE.

WILLIAM HERMAN LUDWIG, OF VESPER, WISCONSIN.

SILO.

1,075,360.

Specification of Letters Patent. Patented Oct. 14, 1913.

Application filed July 24, 1911. Serial No. 640,354.

To all whom it may concern:

Be it known that I, WILLIAM H. LUDWIG, a citizen of the United States, residing at Vesper, in the county of Wood and State 5 of Wisconsin, have invented a new and useful Silo, of which the following is a specification.

This invention relates to silos and its principal object is to provide a silo the hoops 10 of which are adjustably connected to cross rods or rungs extending transversely within the door frame whereby the various hoops can be readily adjusted by a person ascending the ladder formed by said rungs, this 15 being a particularly desirable feature in stave silos wherein more or less shrinkage of the staves occurs and necessitates the tightening of the hoops.

A further object is to provide a door 20 frame having removable cross rods or rungs whereby a person may enter the door opening while in an erect position.

A further object is to provide a novel 25 form of silo roof or cover made up of separately shiftable sections whereby the filling and packing of the silo is facilitated.

Another object is to provide an improved 30 form of locking element which may be applied to the rungs without removing said rungs from the door frame.

Another object is to provide a silo door 35 having steps therein which can be used with the cross rods connected to the sides of the door frame.

A still further object is to provide improved means for splicing together short 40 lengths of staves, the joints being self-draining so as to prevent moisture from entering the silo through the joints.

A further object is to provide an improved 45 form of anchor for holding stay wires to the ground, said anchor being adapted to be used in connection with a novel form of wire tightener.

With the foregoing and other objects in 50 view which will appear as the description proceeds the invention resides in the combination and arrangement of parts and in the details of construction hereinafter described it being understood that changes in the precise embodiment of the invention herein disclosed can be made within the scope of what is claimed without departing from the spirit of the invention.

In the accompanying drawings the preferred forms of the invention have been, 55 shown.

In said drawings:—Figure 1 is a front elevation of a portion of a silo and its door and also showing the connection between a 60 hoop and one of the rungs in the door frame. Fig. 2 is a perspective view of a portion of the silo, showing the connection between one 65 end portion of the hoop and the rung. Fig. 3 is a plan view of a portion of a hoop of a modified form, the same being shown extended completely across the door opening, a portion of the silo being shown in section. Fig. 4 is a perspective view of a portion 70 of a spliced stave. Fig. 5 is a detail view of one of the locking elements employed for securing a door section in position in the door frame. Fig. 6 is a front 75 elevation of a modified form of cross bar or rung, the same being detachably connected to the sides of the door frame. Fig. 7 is a plan view of the rung and its connections shown in Fig. 6. Fig. 8 is a perspective view of another form of rung and its 80 connections.

Referring to the figures by characters of reference 1 designates a portion of the body of the silo, said body being preferably made of staves tongue and grooved and in most instances, these staves extend throughout the height of the wall of the silo. Where it is necessary to splice the staves, however, the upper end of the lower section of the stave is formed with a rounded upwardly extending tongue, such as indicated at 2 in Fig. 4, 90 said tongue projecting into a corresponding groove 3 formed in the lower end of the next adjoining section thereabove. By assembling the stave sections in this manner, the joints are self-draining and there is no danger of moisture filtering through the joint and into the silo.

The silo is fitted with a door frame 4 of the same construction as that disclosed in Patent No. 979,679, issued to me on December 10, 1910, said frame being provided with transversely extending rods 5 forming rungs. In the present instance, however, these rungs constitute sections of hoops extending around the silo. In this construction shown in Figs. 1 and 2 each of the rungs 5 has its screw threaded end portions extended 105 through the sides of the frame 4 and into

elongated lugs 6 which bear against the sides of the frame 4 and against the adjacent portions of the silo wall, the ends of the rungs 5 being held within these lugs by means of 5 nuts or the like. Each hoop also includes, in addition to the rung 5 and lugs 6, a band indicated at 7, and which has its end portions extending slidably into the end portions of the lugs 6 and provided with adjusting nuts 8. Heavy coiled springs 9 are arranged within the lugs and bear at one end against the nuts 8 and at their other ends against the lugs so as to exert a constant pull upon the band and thus cause it 15 to bind continuously upon the staves and promptly take up any looseness in the joints due to the contraction of the staves. It will be noted that the lugs are all arranged along the sides of the door frame and it is thus 20 possible for a person to use the rungs 5 as a ladder and to thus readily reach the nuts 8 for the purpose of adjusting the bands 7 and increasing the stress of springs 9. This is, 25 obviously, an important improvement over ordinary silo structures wherein ladders have necessarily been employed for the purpose of taking up slack in the hoops these ladders being erected at different points along the walls of the silos.

30 If desired certain of the rungs 5, or, if preferred, all of them, can be detachably mounted. In Figs. 6 and 7 the lugs 6 have been shown engaging threaded stems 10 projecting through the sides of the door frame 4 and provided with heads 11. These heads have sockets 12 in the upper faces thereof and said sockets receive knobs or enlargements 13 formed at the ends of a cross bar or rod constituting a rung 14 which may 40 likewise be considered a section of the hoop. Obviously, by removing the rung 14 from engagement with the heads 11, the door opening is cleared of obstructions and a person can then enter the door opening while 45 walking erect.

Instead of forming sockets upon the stems as shown in Figs. 6 and 7, eyes 15 may be formed upon the stems 16, there being collars 17 on the stems for limiting their movement through the sides of the door frame. 50 These eyes are adapted to receive fingers 18 formed at the ends of a rung 19 and extending at right angles therefrom.

In Fig. 3 one end portion of the band 20 55 has been shown extended entirely across the door opening and secured to one end of the lug 21 while the other end of the band is extended loosely into the other end of the lug and has an adjusting nut 22 thereon 60 bearing against one end of a spring 23, the other end of said spring bearing against one end of the lug 21. In this construction the band constitutes the rung of the ladder formed by the door frame and means for 65 tightening the hoop are still maintained

close to said ladder where they can be readily reached by a person standing on one of the rungs. In this form of device cross braces such as indicated at 24 are interposed between the sides of the door frame and directly back of the hoop; said braces being preferably recessed longitudinally along their outer faces, as indicated at 25, so as to form spaces between the hoop and the cross strip whereby said hoop can be used as a 75 hand hold or grip by a person using the ladder.

From the foregoing description it will be seen that in each of the forms described the hoops are extended across the door opening 80 so as to form ladder rungs, these rungs, in the structure shown in Figs. 1 and 2, being made up of separate sections to which the ends of the band are connected by the lugs, the structure in Figs. 6, 7 and 8 having detachable hoop sections extended across the door opening and the structure shown in Fig. 3 showing the main hoop portion or band extended across the door opening, separate hoop sections being eliminated. 85

The doors used for closing the frame 4 may be of any desired construction but are preferably similar to those disclosed in my patent hereinbefore mentioned. These doors, however, can be made up of one or more sections hingedly connected, as indicated at 95 26, and each door section may be provided, in addition to an inclined keeper or handle 27, with a step 28 made up of a rod having offset end portions secured to the cleats 29 upon the door sections 30, each step being 100 preferably located adjacent the central portion of the door section, while the keeper 27 is located adjacent the upper end portion thereof. Silo fasteners 31 are mounted on the rungs 5 of the ladder and are movable into engagement with the inclined keepers 27 so as to securely hold the door sections in closed positions. Each of these fasteners is 105 mounted to slide as well as to rotate upon the rung 5 but that portion of the fastener engaging the rung is preferably in the form of an open eye such as shown at 32 in Fig. 5. By providing this form of eye, the fastener can be applied to the rung without detaching said rung from the door frame and by then bending the eye to closed position, as indicated by dotted lines in Fig. 5, the fastener will be held securely upon the rung. 110

While the structure has been shown and 115 described applied to a silo it is to be understood that the same can be used in connection with tanks and any other structures requiring the use of a binding hoop.

Importance is attached to the fact that 120 where a hoop such as herein described is employed all parts of the longitudinal axis of the band are in the same plane and the ends of the band are extended along straight lines so that, when the hoop is tightened, the hoop 130

is not distorted as would be the case should adjusting means be attached to a curved portion of the hoop.

It is to be understood that other forms of 5 lugs than those shown and described may be provided for connecting the ends of the hoop to the silo or tank.

The term "silo" as used in the claims is not intended to restrict the invention to a 10 silo structure but is to be understood as including tanks or any other structures with which the hoops may be used.

The springs 9 can be dispensed with whenever found practical or desirable and instead 15 of using lugs such as shown at 6, the straight ends of the hoop section 7, can be extended diagonally through the end portions of a cross brace such as shown at 24 and adjustably held by nuts or the like.

20 What is claimed is:—

1. A silo including a door frame having a portion outstanding from the silo wall, lugs bearing against the sides of the outstanding portion of the frame, means extending 25 through the frame for tying the lugs thereto, and a hoop having its ends adjustably engaging the respective lugs.

2. A silo having a door opening, lugs secured to the silo wall adjacent opposite sides 30 of the opening, a hoop having its ends con-

nected to the lugs, and a tie and spacing element connecting the lugs, spanning the door opening, and arranged in the same horizontal plane with the hoop.

3. The combination with a silo having a, 35 door frame, of stems extending through said frame, a hoop section bearing downwardly on and detachably engaging the stems to tie them together, and constituting a ladder rung, and another hoop section adjustably 40 connected to said stems, said sections and stems constituting an endless hoop.

4. The combination with a silo having a door frame, of stems extending through the frame, a hoop section connected to and lift- 45 able out of engagement with the stems and extending across the door opening to tie the stems together, said section constituting a ladder rung, lugs engaged by the stems, and a hoop section adjustably connected to the 50 lugs, said sections, lugs and stems forming an endless hoop.

In testimony that I claim the foregoing as my own, I have hereto affixed my signature in the presence of two witnesses.

WILLIAM HERMAN LUDWIG.
